US00D900290S

(12) **United States Design Patent** (10) **Patent No.:** **US D900,290 S**
(45) **Date of Patent:** **** Oct. 27, 2020**

(54) **AIR PURIFIER**

(71) Applicant: **SAMSUNG ELECTRONICS CO., LTD.**, Suwon-si, Gyeonggi-do (KR)

(72) Inventors: **Young-Sun Shin**, Seoul (KR); **Jin-Sun Park**, Seoul (KR)

(73) Assignee: **SAMSUNG ELECTRONICS CO., LTD.**, Gyeonggi-Do (KR)

(**) Term: **15 Years**

(21) Appl. No.: **29/658,733**

(22) Filed: **Aug. 2, 2018**

Related U.S. Application Data

(63) Continuation of application No. 29/604,210, filed on May 16, 2017, now Pat. No. Des. 827,799, which is a continuation of application No. 29/531,499, filed on Jun. 26, 2015, now Pat. No. Des. 790,050.

(30) **Foreign Application Priority Data**

Dec. 26, 2014 (KR) 30-2014-0063391

(51) **LOC (12) Cl.** **23-04**

(52) **U.S. Cl.**

USPC **D23/364**

(57)

CLAIM

The ornamental design for an air purifier, as shown and described.

DESCRIPTION

FIG. 1 is a perspective view of an air purifier, showing our new design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken lines in the figures are for environmental purposes only and form no part of the claimed design.

1 Claim, 6 Drawing Sheets
